BREECH CLOSING MECHANISM

Filed Sept. 11, 1919

FIG. 1.

FIG. 2.

FIG. 3.

FIG. 4.

UNITED STATES PATENT OFFICE.

TOM THORNYCROFT, OF WESTMINSTER, ENGLAND.

BREECH-CLOSING MECHANISM.

Application filed September 11, 1919. Serial No. 323,211.

To all whom it may concern:

Be it known that I, TOM THORNYCROFT, a subject of the King of Great Britain and Ireland, residing at the city of Westminster, England, have invented Improvements in Breech-Closing Mechanism, of which the following is a specification.

In the specifications of former Patents No. 1,320,659, No. 1,320,661, No. 1,328,021 and No. 1,340,689, there are described means for producing by the combustion of a propellant, such for example as cordite, gases under pressure for use in guns for throwing projectiles such for example as bombs, depth charges and the like and for use in torpedo launching cylinders. In such means or apparatus the propellant is placed in a chamber, called the charge container, that is screwed into a gas receiver into which the gases produced by the combustion under high pressure of the cordite charge, pass and from which the gases flow at a lower pressure to the barrel of the gun, or to the torpedo launching cylinder, as the case may be. Usually the cordite charge has been made up as a cartridge that is inserted into the charge container through the inlet or breech end thereof and held therein by a firing device, commonly called a firing pistol, that is screwed into the breech end of the charge container, after the charge has been placed in position, and afterwards unscrewed and removed to withdraw the empty cartridge case and admit of another cartridge being inserted in the container.

In practice it is found that, in some cases, particularly with depth charge throwers such as described in the said former specification No. 1,340,689, it would be of great advantage if the cartridges could be inserted in the charge container and the empty cartridge cases extracted, in a quicker and more convenient manner than has heretofore been practicable with the removable firing pistol heretofore used.

Now the present invention has for its object to provide the charge container with breech closing mechanism so constructed that cordite or like cartridges can be inserted

in place in the charge container, the breech of the charge container effectually closed, the cartridge fired and the empty cartridge case ejected, all in a rapid and convenient manner.

For this purpose the outer or breech end of the charge container is provided with a movable breech closing block carrying the firing device or pistol, with hand operated mechanism for moving the breech block into its open and closed positions and with a cartridge ejector, the arrangement being such that upon moving the hand operated mechanism in one direction, the breech block will be moved into the open position to admit of the insertion of a cartridge in the charge container, the rim on the cartridge case acting to move the cartridge ejector into its inoperative position automatically. On moving the said mechanism in the reverse direction the breech block will be moved into a position to effectually close the breech end of the charge container and bring the firing device centrally over a percussion cap on the cartridge ready for firing the latter and on again moving the mechanism in the first direction to open the breech, after firing the cartridge, the cartridge ejector will be operated in such a manner as to cause it to eject the empty cartridge case either partially so that it can be finally removed by hand, or completely to eject it from the charge container.

Associated with the hand lever is a spring device adapted to assist the opening and closing movements of the breech block.

Breech closing mechanism to act in the manner described can be constructed in various forms.

Associated with the breech closing mechanism may be means whereby it can be readily ascertained by sight or touch, or both, whether a cartridge is within the charge container or not.

In the accompanying drawings, Fig. 1 is an elevation of one constructional form of mechanism embodying the invention. Fig. 2 is a central vertical section at right angles to Fig. 1, the breech being closed and Fig. 3

is a fragmentary view of a portion of Fig. 2 with the parts in position, to permit a cartridge to be withdrawn. Fig. 4 is a view similar to part of Fig. 3 showing a modification, with a cartridge partly withdrawn.

As here shown the breech end portion of the cartridge container *a*, which is adapted to be screwed into a gas receiver as heretofore, is provided with a head or holder *b* formed with a transverse guide-way *c* the opposite sides of which are formed with a pair of inclined grooves *d*. Fitted to slide in the guideway is a breech block *e* the opposite sides of which are provided with lugs or extensions, not shown, arranged to slide endways in the said grooves. To a lateral extension *b'* of the holder *b* is pivoted, as at *f*, one, namely *g*, of the short arms of a L shaped hand lever *h* the other short arm *i* of which is jointed to one end of a link *j* the other end of which is jointed at *j'* to one end of the breech block *e*. To the lateral extension *b'* of the holder *b* is fixed one end of a bent over spring blade *k* arranged to act against the arm *g* of the hand lever *h*. Pivoted to the holder *b* at *a'* at a point below the path of the breech block *e*, is a cartridge ejector in the form of a bent lever *m*, *n*. The free end of the arm *m* of this lever terminates close to the inlet in the breech end of the charge container *a* through which a cartridge is passed, so as to be in the path of the rim *o'* on the cartridge *o* inserted in the container which is formed with an annular recess or shoulder *a'* for such rim. The free end of the other arm *n* of the ejector lever is arranged in the path of the breech block *e* so as to be operated by this block when being moved into the open position. The breech block *e* carries a firing device or pistol that may be of the kind described in the said former specification No. 1,340,689. The body *p* of such pistol may conveniently be formed in one piece with the breech block *e*, as shown, or it may be made separate and be secured to the block which, in each case, is formed with an aperture *p'*, conveniently of conical shape, through which the firing pin *p''* of the pistol can pass and explode the cap in the cartridge case when the breech block is closed.

The arrangement is such that when the hand lever *h* is moved in one direction about its pivot *f*, and against the action of the spring blade *k*, the connecting link *j* will be caused to assume an angular position, corresponding nearly to that shown in Fig. 3, and draw back the breech block *e* into its open position, the said breech block towards the end of its travel striking the outer end *h* of the ejector lever *m*, *n* so as to move the inner end *m* of such lever outward. Upon inserting a cartridge in place in the charge

container *a*, the lever *h* being held in the opposite extreme position to that shown in Fig. 2, the rim *o'* of the cartridge will engage the inner end *m* of the ejector lever, the latter receding automatically in the act of closing its breech. Upon moving the hand lever *h* in the reverse direction, the breech block *e* will be caused to move backward and inward and bear against the closed end of the cartridge and the surrounding seat on the charge container *a* (see Fig. 2) and effectually close the breech end of such container at the same time bringing the firing pin of the pistol centrally over the percussion cap in the cartridge *o*. After firing the cartridge, upon turning the hand lever *h* sharply to withdraw the breech block *e* and to open the breech, the said block will, after opening the breech strike the outer end *n* of the ejector sharply and cause the inner end *m* thereof to act quickly on the rim *o'* of the cartridge case so as to cause the cartridge case, assisted by its inertia, to be withdrawn from the container, at least to a sufficient extent to enable it to be held by the breech block *e* upon this block moving backward towards it which it will do by rebound and under the action of the spring *k* when abruptly released. In this position of the breech block shown in Fig. 3, the rim *o'* on the cartridge *o* bears against the outer side of the breech block. The further removal of the cartridge case can be effected by hand.

The bent spring blade *k* is, as shown, so arranged in relation to the corner *l* of the lever arm *g* that it will assist the final closing movement of the breech block when operated by the hand lever, as indicated by the arrow in Fig. 2, as well as assisting the opening movement for a time until the spring engages the flat surface *g'* between the corners *1* and *2* of the lever arm after which the spring blade acting on corner *2* tends to move the breech block *e* in the closing direction, indicated in Fig. 3.

Or, instead of moving back the breech block *e* to arrest the partly withdrawn cartridge case, there may be fixed to the holder *b* as shown in Fig. 4, one end of a bent spring blade *q*, the other and free end of which blade is adapted to project into the path of the partly withdrawn cartridge case and hold the case in position to be finally removed by hand.

To enable it to be readily determined whether there is a cartridge within the charge container *a* when the breech block *e* is closed, the hand lever *h* may, as in the example shown, be made tubular and be provided with a pin *r* one end of which is arranged to bear against the end *n* of the ejector lever whilst the other end of the pin is acted upon in an inward direction by a

spring, for instance a coiled spring *s* held in place by a cap *h'* and is adapted to extend through the outer end of the hand lever. In this case the end of the breech block *e* that is adjacent to the end *m* of the ejector lever when the block is in its closed position (Fig. 2), is formed with a recess *t* into which the said end *m* of the ejector lever can pass, under the action of the spring pressed pin *r*, when no cartridge is in the charge container but out of which it will be held, against the action of the spring pin, by the rim *o'* of a cartridge *o* held within the charge container. In the former case the outer end of the spring pin *r* will not extend beyond the end of the hand lever *h* and in the latter case it will project beyond such end of the lever, as shown, thus serving as an indicator to enable the operator to see, or to determine by touch, whether there is a cartridge in the charge container or not. This indicating arrangement will also serve to indicate when the breech block is fully moved into its closed position.

The safe working of the mechanism is provided for automatically by the fact that the percussion cap in the cartridge is only slightly larger in diameter than the point of the firing pin or hammer by which it is detonated so that unless the breech block is fully closed the firing pin cannot strike the cap.

The details of construction of breech closing mechanism according to the invention can be variously modified to suit requirement.

What I claim is:—

1. The combination with the breech end of a cartridge container having a holder with transverse guideway therein, a breech block adapted to slide in said guideway and to coact with said holder to close the breech end of the container, a firing device carried by said block and a cartridge ejector adapted to be moved in one direction upon inserting a cartridge in the container and in the opposite direction by the block when moving into its open position, of a hand operated lever having one end jointed to the holder, a link connection between another end of the lever and the block and a spring adapted to assist both the opening and closing movements of the block.

2. The combination with the breech end of a cartridge container having a holder with transverse guideway therein, a breech block adapted to slide in said guideway and to coact with said holder to close the breech end of the container, and a cartridge ejector adapted to be moved in one direction upon inserting a cartridge in the container and in the opposite direction by the

block when moving into its open position, of a hand operated lever having one end jointed to the holder, a link connection between another end of the lever and the block, and a spring adapted to act against one or other corner of the end of the lever jointed to the holder and thereby assist the opening and closing movements of the block when the lever is moving into positions to respectively open and close the block.

3. Breech closing and opening mechanism according to claim 2, wherein the hand lever is of T shape, one of its short arms being jointed to the holder and its other short arm to the link and the spring is a blade spring fixed to the holder and arranged to act against one or other of flattened corners of the lever arm jointed to the holder.

4. The combination with the breech end of a cartridge container provided with a holder of a breech block adapted to slide in said holder, a cartridge ejector jointed to the holder and having an arm arranged to project into the path of the rim of a cartridge being inserted in the container and an arm arranged in the path of the block so as to be moved by such block when moving into its open position, a hand lever for opening and closing said block, and an indicating device carried by said hand lever and arranged to coact with the cartridge ejector to give an indication whether or not a cartridge is in the container when the block is in its closed position.

5. The combination with the breech end of a cartridge container provided with a holder, of a breech closing block adapted to slide in said holder and formed with a recess, a cartridge ejector having an arm adapted to be moved into the recess in the block and a second arm arranged in the path of the block when the block is moving into its open position, a hand lever for moving the block into its open and closed positions and a spring controlled indicating device carried by the hand lever and arranged to coact with the second arm of the ejector which second arm acts to hold the indicating device in one or other of two positions according to whether or not a cartridge is within the container, said first arm of the ejector being held out of the recess in the block by said cartridge, or being free to be moved into such recess, when a cartridge is absent, by the indicating device.

6. The combination with the breech end of a cartridge container provided with a holder, of a breech closing block adapted to slide in said holder and formed with a recess, a two armed cartridge ejector having one arm arranged to be engaged by the rim

of a cartridge and capable of entering said recess in the block when a cartridge is absent and the second arm arranged to be actuated by the block when moving into its open position, a hand lever for moving said block into its open and closed position and having a tubular arm to be grasped by the hand, a pin arranged to slide endways in said tubular arm and having its outer end

10 adapted to extend through the free end of the tubular arm and its other end arranged in the path of the second arm of the ejector and a spring arranged to press the pin

against the last mentioned ejector arm, substantially as described for the purpose set forth.

7. Breech closing mechanism according to claim 1 wherein a spring device is arranged on the charge container adapted to hold a partially ejected cartridge case until it can be removed by hand, substantially as described.

Signed at London, England, this twenty first day of August, 1919.

TOM THORNYCROFT.
